Int. Cl. D8—02

U.S. Cl. D8—99

FIG. 1 is a perspective view of a pocket knife showing my new design;

FIG. 2 is a top plan view thereof on a reduced scale;

FIG. 3 is a bottom plan view thereof on a reduced scale;

FIG. 4 is a side elevation thereof;

FIG. 5 is a top plan view of a modified form of the design of FIG. 1 on a reduced scale, wherein the detents are angled in an offset relationship; and

FIG. 6 is a top plan view of a further modified form of the design of FIG. 1 on a reduced scale, wherein the detents are arcuate.

I claim:

The ornamental design for a pocket knife or similar article, substantially as shown and described.
